CLAIM

The ornamental design for an inverted pouch, as shown and described.

DESCRIPTION

FIG. 1 is a front perspective view of the inverted pouch showing our new design;
FIG. 2 is a front elevational view thereof;
FIG. 3 is a right side view; the left side view being a mirror image thereof;
FIG. 4 is a rear elevational view thereof;
FIG. 5 is a bottom view thereof; and,
FIG. 6 is a top view thereof.

1 Claim, 5 Drawing Sheets
